MANIFOLD CARBON COPY DEVICE

Robert J. Copeland, Toronto, Ontario, Canada

Application May 4, 1934, Serial No. 723,811
In Canada April 4, 1934

6 Claims. (Cl. 282—28)

The principal objects of this invention are to provide a multiple arrangement of manifolding carbon sheets particularly adapted for use with continuous record sheets which will permit 5 the easy movement of the carbon sheets lengthwise of the record sheets when they are being shifted and which will not be liable to catch on the transverse perforations of the record sheets and be torn thereby.

10 A further and important object is to provide a manifolding device which will greatly facilitate the insertion and threading of the record sheets therethrough, and still further, to effect economy in the cost.

15 The principal feature of the invention consists in securing one end of each of the carbon sheets to a thin reinforcing strip and fastening the ends of the reinforcing strips to a backing sheet of strong durable material, the reinforcing members being preferably folded and presenting a rounded edge to slip over the surface of the continuous record sheets.

20 A further and important feature consists in the novel manner of further reinforcing the folded strips with a thread or cord sealed in the folded edge.

25 In the accompanying drawing, Figure 1 is a perspective view of a manifold carbon copy device constructed in accordance with this invention.

30 Figure 2 is an enlarged perspective detail illustrating the manner of arranging the reinforcing strips upon the end of a carbon sheet to be used in this device.

35 Fig. 3 is a perspective detail showing a modified arrangement of means for securing and reinforcing the carbon sheets.

40 Fig. 4 is an enlarged and exaggerated perspective detail of a portion of the latter form of reinforcement as illustrated in Figure 3.

45 Fig. 5 is a diagrammatic sectional view showing the manner in which the device is used in continuous record form sheets.

Fig. 6 is a view similar to Fig. 5 illustrating 50 the use of the carbon sheet backing as a means for guiding separate paper sheets into the typewriter.

In the practical application of this invention 55 a sheet 1 of a strong tough paper such as manila, is cut approximately an inch wider than the continuous record sheets with which the duplicating device is to be used.

Several sheets of carbon paper 2 are arranged centrally of the width of the manila sheet and 55 each of said carbon sheets is fastened to a cross

strip 3 of thin tough paper, the ends 4 of which are secured to the marginal edges 5 of the main sheet 1, the central portions of these cross strips being unsecured for a width slightly greater than that of the record strips 6 or sheets which are of slightly greater width than the carbon sheets.

5 The record sheets can thus be threaded between the manila backing sheet 1 and the first of the carbon sheets and the other sheets 7 and 8 are threaded between the adjacent carbon 10 sheets.

In preparing the carbon sheets for attachment to the backing sheet the carbon sheets may be formed as shown in Figure 2 with a selvedge edge 9 free of the carbon preparation.

15 The cross strip 3 which is gummed on one side and is of greater length than the width of the carbon sheet, is secured to the back of the carbon sheet along the selvedge edge and it is then folded longitudinally and secured to the other side. 20 The folding of this strip over the edge of the carbon sheet protects the carbon from catching upon the projecting portions of perforations in the record sheets as it threads through between the carbons and it also presents a rounded edge 25 which will slip over any projections.

It may be found desirable to further reinforce this folded edge strip and also to enhance the rounded feature, and this is accomplished in a very simple manner by laying a thread or cord 30 10 along the folded edge above the edge of the carbon sheet and sealing it in place therein as is shown in Figures 3 and 4.

This cord not only provides a desirable rounded end edge for the carbon sheet and a reinforcement therefor, but it will be seen on reference to Figures 1, 3 and 4 that it extends beyond and clear of the carbon sheet so that it will function to afford a secure anchorage to the medium 35 to which the carbon sheets are attached.

40 In Figures 3 and 4 I also show a modification of the manner of securing the reinforcing edge strip to carbon sheets. This is particularly adapted where carbon sheets with selvedge edges are not available and as herein shown the carbon sheet is punched with a row of perforations 11 along the edge which is laid over the reinforcing cross strip. The folded over portion of the cross strip when pressed into place will adhere to the other half through the perforations which are proportionately large and allow the two adhesive surfaces of the reinforcing strip to meet therethrough, thus firmly securing the carbon sheet to the strip.

45 The reinforcing edge strips of the carbon 50

sheets are preferably laid one over the other and only slightly offset, thus bringing the edges of the carbon sheets closely adjacent so as to facilitate the easy threading of the record sheet there-
5 between.

- In certain classes of work it is found desirable to use separate or individual "letter" or "form" sheets with continuous duplicates and the bottom edge 12 of the backing sheet 1 presents a lip, 10 forming with the adjacent carbon sheet a pocket into which the edge of the "letter" sheet 13 may be inserted to guide it into position in the type- writer carriage. As shown in Figure 1 in dotted lines, the lip preferably presents an edge which 15 is curved or convexed to facilitate the insertion of the "letter" or "form" in the pocket formed between the carbon sheet and lip.

A special form of carbon "gate" may be used as illustrated in Figure 6 in which the first 20 carbon sheet 14 is fastened over its entire width to the backing sheet 1 spaced from the bottom edge 12 of the sheet 1 to form a pocket, the line of engagement of the carbon sheet with the backing sheet 1 forming a definite stop for the 25 inserted "letter" sheet.

It will be readily seen that when a letter sheet is inserted from the front side of the platen of the typewriter into the pocket provided by the carbon "gate" the said sheet will be guided back 30 into the carriage around the platen with the least possible trouble to the operator.

It will readily be appreciated that a duplicating device such as described may be partly assembled, that is to say, one end of each of the 35 reinforcing end strips of the carbons may be fastened to the margin of the manila backing, with the other ends left free, so that the carbon sheets may be slipped sideways in between a plurality of continuous record sheets without re- 40 pairing the threading of the ends therethrough. After the sheets have thus been inserted the ends of the strips may be fastened to the margins of the backing sheet.

What I claim as my invention is:—
45 1. A manifold carbon copy device comprising

ing sheet of greater width than the carbon sheets, the portion thereof extending beyond the sides of the carbon sheets being secured to the ends of the reinforcing strips extending beyond the carbon.

2. A manifold carbon copy device comprising 5 carbon sheets, folded strips of material embrac- 10 ing and secured one to one end of each of said carbon sheets and extending beyond the side edges thereof and forming a rounded protected 15 edge for the carbon sheets, and a backing sheet of greater width than the carbon sheets having the extension end portions only of the reinforcing strips of said carbon sheets attached to the side marginal portions thereof with the rounded 15 edges spaced from each other.

3. In a manifold carbon copy device, carbon 20 sheets having a selvedge edge, folded strips of fibrous material embracing and cemented to said selvedge edge and projecting beyond the 25 sides of the carbon sheets, said strips being laid one over the other in stepped arrangement, and a backing sheet of greater width than the carbon sheets having the marginal portions secured to the ends only of the folded strips carrying said 25 carbon sheets.

4. A manifold carbon copy device, comprising 30 carbon sheets, folded strips of fibrous material secured to one edge of each of said carbon sheets, a reinforcing cord arranged in the fold of said 35 strips, and a backing sheet having the ends of said folded reinforced strip extending beyond the carbon sheets secured to the marginal edges thereof, leaving the central portion free.

5. A manifold carbon copy device comprising 35 a carbon sheet and a backing attached to one end of the carbon sheet and extending partly thereunder presenting a free guiding lip, said lip terminating in a convexed edge to facilitate the 40 insertion of an individual letter sheet or form 45 between the lip and carbon sheet.

6. In a carbon copy device, a carbon sheet having one edge reinforced by a cord extending longitudinally thereof, the cord and sheet being secured together and said cord being extended clear of the carbon sheet to form a secure anchorage for the sheet.

ROBERT J. COPELAND.
